METHOD AND APPARATUS FOR FORMING A TEXTILE MATERIAL WITH AN ADHESIVE TYPE SELVAGE

Richard D. Wood, Jr., Wawa, Pa., and Charles T. Gould, Walpole, Mass., assignors to The Millville Manufacturing Co., Millville, N.J., a corporation of New Jersey
Continuation of application Ser. No. 820,921, June 17, 1959. This application Jan. 9, 1962, Ser. No. 167,999
11 Claims. (Cl. 117—4)

This invention relates to improvements in method and apparatus for forming a textile material with an adhesive type selvage, and more particularly the invention is concerned with the high speed production, from a continuous web of textile material, of articles, such as diapers, towels, handkerchiefs, industrial wipe-up cloths and the like, which are cut off from the web and whose cut edges are secured adhesively by plastic or resin bands.

This application is a continuation of our previous application Serial No. 820,921, filed June 17, 1959, now abandoned, which, in turn, is a continuation-in-part of our previous application Serial No. 742,788, filed June 18, 1958, now abandoned. The latter abandoned application was a continuation-in-part of our earlier application Serial No. 568,115, filed February 27, 1956, now United States Patent No. 2,852,407.

As is well understood, the word "selvage" refers to an edge of a fabric so formed as to prevent raveling. Normally, in the weaving of a fabric, the opposite longitudinal side edges of the fabric are formed with a natural selvage. When the fabric is cut up into individual articles, the cut fabric edges normally are secured by an artificial selvage, such as a sewn hem.

In recent years, great progress has been made in the development of adhesive type selvages for cut fabric edges, which take the place of sewn hems. The adhesive selvage technique has come to have a recognized status in the art, being commonly referred to as "resin hemming" or "plastic hemming." Early embodiments of methods and apparatus for carrying out the adhesive selvage technique are disclosed in United States Patents Nos. 2,740,457 and 2,852,407. Reference may be had to both of those patents and also to United States Patents Nos. 2,744,844 and 2,753,287 for disclosures of satisfactory resin or plastic compositions suitable for use in the practice of the present invention.

The present invention is based preferably on the use of high frequency dielectric curing or setting to effect high speed hemming of the type referred to, and in one preferred form deals with treatment of cotton textile webs of a type suitable for diaper use. It is intended, however, that the invention should not be limited to diapers, but may be employed for processing various other types of textile webs in producing cut textile articles, as above noted.

Unusual problems are encountered in carrying out a high speed method of plastic or resin hemming in which narrow bands of an adhesive are periodically impregnated or otherwise applied at spaced intervals transversely of a web of fabric and advanced at a uniform rate through successive curing and cutting stations. To increase the rate of production of cut textile articles to a high level, for example to forty units per minute and higher, the time of cure of the resinous or plastic adhesive is required to be shortened to an interval of appreciably less than one second and the curing action must be carried out all the way through the impregnated adhesive band without detriment to either the cloth or the adhesive.

The problems are rendered more difficult by reason of the fact that an elongated, narrow band of plastic or resin in fabric or cloth is not an ideal material to undergo dielectric heating, and requires a very uniform,

2

narrow electric field which, in turn, introduces problems and special requirements in electrode design and handling. Having regard to the dimensional instability of fabrics, arising from the variations in the residual strains therein, it will be appreciated that great difficulty is presented in moving successive, narrow bands of an adhesive at high speeds into precise register with a narrow electric field. Such variable residual strains in fabrics develop, of course, as a result of the techniques of present day, 5 high speed finishing operations where severe, uneven jerking, tugging, stressing and stretching of the fabric repeatedly occurs, resulting in variable stretch characteristics throughout the fabric.

It is a chief object of the invention to deal with the 15 problems indicated, and to devise improved methods and apparatus whereby there may be carried out more rapidly and efficiently, and at lower costs, in resin hemming, the steps of impregnating, curing and cutting in a properly synchronized relationship to one another.

Another object of this invention is to provide a method 20 of combining an adhesive material with the cut ends of a textile article in a manner such that a more intimate impregnation of the adhesive is accomplished, more uniform cure realized and the resistance of the resulting resin hem to deterioration from washing is significantly increased.

Still another object is to devise resin hemming apparatus in which there are combined, with adhesive applying and adhesive curing apparatus, a number of special 25 tension control devices which can be regulated uniquely in accordance with variable stretch characteristics of the fabric being hemmed to maintain uniformity of processing.

A still further object of this invention is to provide a 30 high speed method of resin hemming whereby the cloth or fabric is stretched to an extent at least equal to any residual strain therein so as to be advanced in a state of uniform elongation to successive adhesive application, curing and cutting stations.

A still further object of this invention is to provide a 35 high speed method of resin hemming wherein the cloth is advanced and maintained in a state of substantially stabilized or uniformized elongation, whereby the cloth advances uniformly to successive adhesive application, curing and cutting stations.

A still further object of this invention is to provide a 40 high speed method of resin hemming whereby the cloth is advanced intermittently to adhesive application, curing and cutting stations under tension sufficient to stretch the cloth an amount at least equal to any residual strain therein, and is stopped periodically and releasably held in a stretched condition, under a tension sufficient to achieve equilibrium while the fabric is at rest, for proper adhesive registration at the curing and cutting stations.

A still further object of this invention is to provide a 45 high speed method of curing a resinous or plastic adhesive, impregnated in a fabric, by dielectric heating apparatus so controlled as to cure or set the adhesive completely throughout its cross section, in a very short interval of time, without charring the fabric or impairing any of the adhesive components.

An additional object of this invention is to provide a 50 method of applying a metered amount of adhesive transversely of a web of cloth or fabric to form a band thereon which is thinner along its transverse edges than at its median portion, and forcing the adhesive under pressure into and between the fibers of the cloth along the band.

These and other objects and novel features of this 55 invention will be more fully understood and appreciated from the following description of a preferred embodiment of the invention selected for purposes of illustration and shown in the accompanying drawings, in which:

FIG. 1 is a diagrammatic view of a preferred embodi-

ment of the invention indicating schematically a web of cloth or fabric being passed through the various processing stations.

FIG. 2 is a diagrammatic view illustrating apparatus for supporting a roll of cloth.

FIG. 3 is an enlarged fragmentary view in perspective illustrating diagrammatically a web of cloth which has been impregnated with a band of cured resin in accordance with this invention.

FIG. 4 is a view in top plan of a preferred cloth hemming machine for carrying out the operations indicated in FIG. 1.

FIG. 5 is a view in side elevation of the machine shown in FIG. 4.

FIG. 6 is an enlarged fragmentary view in side elevation illustrating the special multiplier tensioning means of the invention.

FIG. 7 is a view similar to FIG. 6 showing an intermediate portion of the machine.

FIG. 8 is a view similar to FIG. 6 showing the front of the machine.

FIG. 9 is a fragmentary view in perspective of the front of the machine as viewed from one side thereof.

FIG. 10 is a view in side elevation showing the opposite side of the machine from that indicated in FIG. 5.

FIG. 11 is a fragmentary view in section taken approximately on the line 11—11 of FIG. 10.

FIG. 12 is a fragmentary view in section taken approximately on the line 12—12 of FIG. 11.

FIG. 13 is a fragmentary view in section taken approximately on the line 13—13 of FIG. 12.

FIGS. 14 to 18 inclusive are detail fragmentary views in section illustrating the application of adhesive to cloth by the apparatus of the invention.

FIG. 19 is a fragmentary view in section taken approximately on the line 19—19 of FIG. 10.

FIG. 20 is a fragmentary detail view in side elevation of one pair of electrode components of the dielectric heating apparatus.

FIG. 21 is a fragmentary transverse view in cross section of one pair of electrode components.

FIG. 22 is a fragmentary view in section taken approximately on the line 22—22 of FIG. 19.

FIG. 23 is a fragmentary view in section taken approximately on the line 23—23 of FIG. 19.

FIG. 24 is a diagrammatic view showing lines of high potential in relation to an adhesive band.

FIG. 25 is a fragmentary view in section taken approximately on the line 25—25 of FIG. 19.

FIG. 26 is a fragmentary view in perspective showing the drive mechanism removed from the supporting frame of the machine.

FIG. 27 is a cross section taken approximately on the line 27—27 of FIG. 10.

FIGS. 28 and 29 are details of a cam mechanism occurring in FIG. 27.

FIG. 30 is a diagrammatic view illustrating the timing relationships of the operations carried out by the preferred machine shown in the drawings.

FIG. 31 is a curve showing the rise and fall in cloth tension for a specific bird's-eye diaper cloth processed by the preferred machine shown in the drawings.

In accordance with this invention, we commence with the provision of a portion of a web of fabric or cloth in the form of a freely suspended loop, from which the cloth is delivered for plastic or resin hemming in a state of substantially zero tension (except for its own weight). We then subject the web to a drafting force potentially of a magnitude in excess of the breaking strength of the cloth to advance the cloth at a predetermined speed along a desired path of travel to successive adhesive application, adhesive curing (by dielectric heat) and cloth cutting stations. To generate this drafting force, we employ a pair of rotatable roll members, one of which engages the cloth in a partially wrapped around position and the

other of which provides a nip, adjustable in pressure as desired.

As the cloth is advanced from its substantially tension-free state, it is pulled by the drafting means through retardation means which releasably engages the cloth to apply thereto frictional forces of resistance to tension and stretch the cloth as it advances. Such retardation means includes adjustable tensioning means to vary the frictional forces of resistance and thereby vary the extent to which the advancing cloth is stretched. As will be readily understood, the degree of adjustment of the adjustable retardation means determines the intensity of the drafting force actually exerted upon the web of cloth as it advances to the successive fabric treating stations.

Generally, the cloth processed by this invention has been subjected to the usual finishing processes which, as explained above, induce into the cloth varying residual strains, i.e. varying residual elongations resulting from previous stressing. Often, each roll of cloth to be processed by the invention includes several different sections of cloth stitched together in a continuous length to form a single roll. These different sections of cloth often vary appreciably in their internal residual strains. As a result, cloth processed in accordance with this invention often will have variable stretch characteristics, depending upon the character of the residual strains throughout the fabric. Unless these variations in residual strains are compensated for, the uniform advancement of the cloth web to the adhesive curing and cloth cutting stations, to enable precise registration of the adhesive bands at those stations, will not be realized in a high speed operation.

To overcome this handicap, it is necessary that the retardation means exert sufficient frictional forces of resistance to the advance of the web to subject the cloth as it travels to a tension which is capable of imposing upon the cloth a state of substantially stabilized elongation. That is to say, the cloth, which is subject to variable residual strains, i.e. residual elongations which vary throughout the fabric, is tensioned so as to be stretched throughout an amount to equal or exceed such strains, thereby uniformizing the stretch characteristics of the cloth as it is processed. In this way, the cloth is maintained under tension in a state of stretch which is at least equal to any residual strain in the fabric. By doing so, the fabric, as it advances, will be subjected to a uniform state of stretch with the result that the portions of the web which have been impregnated with the adhesive band will advance uniformly for accurate registration at the curing and cutting stations. By providing adjustable retardation means at the retardation station, it is possible to readily correct the degree of tension control, as required, to stretch the web of fabric sufficiently to compensate for variations of stretch characteristics, and thus ensure precise registration for the successful practice of this invention.

As will be readily understood by those skilled in the art, our invention may be applicable either to continuous or to intermittent plastic hemming operations. Accordingly, while in the preferred embodiment of this invention, as disclosed in the drawings and described herein, the invention is illustrated as applied to an intermittent resin hemming operation, it is to be understood that the invention is readily applicable to a continuous operation, where desired.

The operation of the hemming machine shown in the drawings will be described with reference to a high speed intermittent hemming operation wherein up to forty or more diapers per minute may be produced. At a production rate of forty diapers per minute, each complete hemming cycle is carried out in a time interval of approximately one and one-half seconds. Since a typical diaper length and width may be taken, for the purposes of illustration, as twenty-seven inches each, it will be apparent that each band of resinous adhesive which is applied to the web must advance to the dielectric heating

apparatus at a speed not less than twenty-seven inches per three-quarters of a second. It has been determined that a suitable width for a resin diaper hem is one-quarter inch, which requires the application of a band of adhesive to the web of one-half inch in width. It has also been determined that a narrow electric field of not more than three-quarters of an inch is necessary to get a satisfactory dielectric curing result for a half inch band which extends transversely over a diaper cloth web of twenty-seven inches in width.

As has been stated above, it is highly essential that the band of resin be advanced to register accurately within the electric field. It cannot fall short nor overrun more than one-eighth of an inch without failure of cure. The adhesive band also must register precisely at the cutting station. It is further pointed out that in each cycle of an intermittent operation there is a "travel period" and a "dwell period" and, therefore, as the cloth advances, there necessarily occurs a rise and fall of tension in each successive twenty-seven inch length of cloth. In order to advance each successive length of cloth uniformly through the machine to obtain accurate registration of the band of resin at the curing and cutting stations, the minimum tension exerted on the cloth must, at a drafting roll and braking station B; variably retarding to the maximum residual strain in the cloth, thereby obtaining a uniform state of cloth stretching.

The cloth handling operation and the associated steps of applying, curing and cutting the resin band in the cloth are indicated diagrammatically in FIG. 1. In FIG. 1, there are noted schematically the steps of furnishing a web of cloth W from a cloth supply roll station A; the operation of exerting a drafting force on the web W at a drafting roll and braking station B; variably retarding travel of the cloth W at a tension control station F; engaging the cloth web W at a cloth guiding station C; impregnating a band of resin transversely of the web W at an applicator station D; curing the impregnated resin at a dielectric curing station E; cutting the band of resin at a cutting station G; and removing cut pieces from the machine at a conveyor station K.

The web of cloth W is furnished from a supply roll R by means of a friction drive roll R1 (FIG. 2) and is allowed to form a suspended loop L, as noted at the right hand side of FIG. 1, at which point the cloth is under substantially zero tension, except for its own weight.

In each diaper making cycle, a pair of intermittently driven drafting rolls M and M1 periodically revolve and during the "travel portion" of the cycle exert a drafting force on web W. This drafting force is potentially of a magnitude in excess of the breaking strength of the cloth. At the tension control station F, a series of fixed and adjustable friction bars exert frictional forces of cloth retardation which oppose the drafting force.

Considering in greater detail the apparatus for carrying out the method noted, attention is drawn to FIGS. 4-10 inclusive in which numeral 2 denotes a machine frame comprising a rectangularly shaped enclosure presenting opposite raised sides 4 and 6. At the right hand end of the machine frame, as shown in FIG. 4, is mounted the cloth supply roll R of a textile material of the class already indicated.

For purposes of furnishing a web W from roll R at substantially zero tension, the roll is mounted on inclined bracket supports 7 and 8 which are solidly bolted or otherwise secured to the frame. On their inclined upper ends, these bracket supports are covered with suitable hard fiber wear strips on which is slidably supported the arbor for roll R. Thus, the roll R tends to slide downwardly and is retained in frictional contact against the surface of the driver roll R1 so that rotation of roll R1 unwinds a continuous web from roll R. Roll R1 is positively driven by a motor 9 to which is connected a Reeves drive 10 and a reducer 11. Reducer 11 has a

sprocket 12 driving a chain engaging another sprocket gear 12' fixed on the shaft of the driver roll R1.

By means of the cloth supply arrangement described, a positive unwinding action may be realized at any desired or required speed. This condition is constantly maintained in effect as the diameter of the cloth supply roll R decreases so that the web continually is formed into a loop of cloth, as shown in FIGS. 1 and 10, and the freely hanging loop has substantially no tension on it, except for its own weight.

Preferably, the position of angularity, denoted by the angle ϕ in FIG. 2, of the wear surfaces to the horizontal lies between approximately 17° and 21° . Of course, within the range of angles noted, some variation may be required in accordance with the character of the cloth being unwound.

We may also desire to employ photoelectric cell units as shown diagrammatically in FIG. 1. These units are responsive to change in cloth loop size and are adapted to stop the machine under certain conditions and to control the speed of cloth feed from roll R.

One cell unit is composed of two cells D10 and D12. These cells are arranged in an elevated position at either side of the loop L so that if the loop grows very small in depth the cells are energized and the entire machine operation will shut down.

A second cell unit is composed of cells D14 and D16. These cells are arranged below cells D10 and D12 at either side of the web loop in a position such that if the loop grows shorter, the cells are energized to actuate a circuit to motor 9 for speeding up the cloth supply.

A third unit is composed of cells D18 and D20 which are located below cells D14 and D16 at either side of the web loop in a position to be interrupted by a loop which becomes too deep. In this case a circuit to motor 9 is interrupted, resulting in a slowing down of cloth feed.

From this loop L thus furnished, the cloth web is pulled away by the drafting force exerted through the drafting rolls M and M1. As noted in FIGS. 1, 4, 10 and 26, the rolls M and M1 are transversely disposed within the machine frame and include suitable drive means. The drive means includes a motor 13, Reeves drive 14 and reducer 15, to which is fixed a pinion gear 16 (FIGS. 4, 10).

Meshing with gear 16 is a large gear 17 which drives the main machine shaft 18 (FIG. 10). This main shaft 18, when turned through one complete revolution, produces one complete cycle of machine operation and times the various processing operations. Opposite ends of shaft 18 are supported for rotative movement in a bearing 19 secured to the frame 2 and a second bearing 20 located on a bracket 21 inside the machine frame (FIG. 27).

A crank plate 22 is mounted at one end of shaft 18 and includes a slide 23, in which is received a connecting rod stud 24 and a connecting rod 25 (FIG. 26). The opposite end of the connecting rod is supported forwardly of the machine frame in a slide bearing 26, as shown in FIG. 27. The slide bearing is supported by a shaft 27. Also mounted on shaft 27 is a clutch gear 28 in mesh with a rack 25a on rod 25 (FIG. 26).

The clutch gear 28 is fastened to an over running clutch 29 which, under the influence of rod 25, selectively drives shaft 27 through an arc of rotation proportionate to the length of article to be processed and cut. It should be observed that the connecting rod stud 24 is adjustable with respect to the center of the crank plate 22 to provide varying displacement of rod 25 in accordance with the desired cut length of the article.

Upon rotation of shaft 27 through the crank and clutch mechanism described, a sprocket 30, fast on shaft 27, turns and drives a series of sprockets, including sprockets 32, 33 and 34, through a chain 31. The sprocket 32 is fast on a shaft 35 mounted between metering roll brackets 38 and 39 (FIG. 27) and on this same shaft is solidly secured metering roll M. An important component of this roll assembly is an electric brake 40 mounted

at the end of shaft 35 (FIGS. 5, 26, 27). This brake functions to prevent shaft 35 from over-running or rolling back, and is used to hold an advanced portion of the cloth web in a fixed position as desired. Another component is the roll M1 mounted in rolling contact with roll M on a shaft 41 supported in roll brackets 38 and 39. This roll M1 is driven by roll M through gears 42 and 42a, as shown in FIG. 27.

Cloth Tension Control

The rolls M and M1 are powdered to develop a drafting force potentially of a magnitude in excess of the breaking strength of the cloth. This drafting force, as noted above, is employed to draw the web W forwardly against the resistance of the tension control mechanism of the invention indicated in FIG. 1 at station F.

The tension control mechanism is shown in greater detail in FIGS. 4-6, 10, and includes a set of stationary tension bars and a set of adjustable tension bars. The stationary tension bars are denoted by the numerals 43, 44, and 45 and are supported between the frame sides 4 and 6. Cloth drawn from the loop L by the drafting rolls M and M1 is guided over rod 43, under rod 44 and over rod 45 to provide retardation forces resulting from frictional contact of the rods with the cloth. These friction forces yieldably oppose the drafting force of the rolls.

In accordance with the invention, the fixed tension force thus developed is very greatly increased by the set of adjustable tension rods 46 and 47 which are held together by links 46a (FIG. 6) and arranged to swing on horizontally spaced pivots 48 supported by the machine frames. Similarly, a second set of adjustable tension rods 49 and 50 are joined together by links 49a adapted to swing on horizontally spaced pivots 51. Adjacent to the adjustable rods 49 and 50 are two other fixed tension rods 52 and 52a. It will be observed that changing the position of the rods 46, 47, 49 and 50 will either increase or decrease the area of releasable engagement of those members with the cloth web. When the cloth is in motion, it is drawn tightly against the tension rods or bars to produce a dynamic friction, whereas when the cloth is at rest, it is less tightly drawn against the bars and a static friction is present. The tension rods serve as cloth retardation means which act to oppose the drafting force of the rolls M, M1, and thus stretch the cloth web as it advances in the machine.

The two sets of adjustable tension rods 46, 47, 49 and 50 are controlled by means of gears as shown in FIG. 6. Thus, a gear 53 is fast to a pivot 48 and is rotatable by means of a worm 54 mounted in a worm bracket 54a on the frame. The worm 54 is revolved by means of an operating rod 55 which extends forwardly along one side of the machine to a bearing support on the frame. At the end of the rod 55 is a dial indicator hand wheel 56 best shown in FIG. 9. Similarly, the tension rods 49 and 50 are provided with a gear 57, a worm 58, operating rod 59 and a dial indicator hand wheel 60. The dial indicator hand wheels 56 and 60 are of conventional nature and indicate the arcs of rotation of the tension bars which result from turning the operating rods 55, 59.

It will be seen, therefore, that the hand wheels 56, 60 may be rotated to adjust the position of the tension bars 46, 47, 49 and 50, and thereby vary the frictional retardation forces on the cloth in accordance with any change in the cloth stretch characteristics (i.e. residual strains) at any time. This mechanism for controlling tension exerted on the cloth constitutes a very important feature of the invention and enables us to move successive resin bands from the applicator station D uniformly through the machine into precise register at the dielectric station E and cutting station G.

Thus, as shown in FIG. 6, the cloth is caused by the tension bars 46, 47, 49 and 50 to advance along a sinuous path of travel. Regulation of the tension exerted on the cloth by the tension bars is achieved by varying the curva-

ture of the sinuous path to change the area and intensity of frictional engagement of the cloth with the surface of the tension bars.

By correlating the adjustment of the tension bars with the degree of energization of the brake 40 on the drafting rolls, we are enabled to apply tension to the cloth which at any time—even when the cloth is at rest—stretches the cloth an amount at least equal to any residual strain therein. Such correlated setting of the tension bars will uniformize the stretch of the cloth as it advances and thus enables successive resin bands to advance uniformly through the machine, i.e. the same distance during a selected time interval, to register accurately at the dielectric curing station and at the cutting station. At the same time, such correlated settings of the bars and brake will enable the cloth web to be held in momentary equilibrium by the rolls M and M1 and the tension bars, the latter releasably engaging the cloth, during the "dwell portion" of the cycle. During this period of momentary equilibrium, the cloth, between stations B and F, is maintained under a tension sufficient to stretch the cloth an amount at least equal to the maximum residual strain therein. Thus, during the time interval that the cloth is at rest, the frictional resistance of the tension bars is momentarily in balance with the holding force of the rolls M and M1 to prevent retraction of the stretched fabric during the "dwell portion" of the cycle and thereby maintain the fabric in a state of substantially stabilized elongation.

If the cloth changes in its stretch characteristics significantly, as it may from time to time, loss of register of the resin bands at the curing and cutting stations may result, thus necessitating adjustment of the brake or the tension bars or both. Where the loss of register is slight, compensation preferably may be made therefor by varying the degree of energization of the brake to thereby vary the effect upon the roll M of its own momentum as its rotation is stopped at the end of the "travel portion" of a cycle. An increase or decrease in the energization of the brake will vary in proportion the amount of momentum of the roll absorbed by the brake and thus vary in proportion the precise position at which the roll M, and the advanced portion of cloth passing over it, will stop at the end of the "travel portion" of the cycle. If such adjustment of the degree of energization of the brake is not sufficient to repair the loss of register, then the setting of the adjustable tension bars is changed to increase or decrease their tensioning effect on the cloth to the extent necessary to regain register of the resin bands at the cutting and curing stations. Of course, if desired, loss of register may be repaired solely by resetting the adjustable tension bars.

As a typical intermittent cycle starts, the drafting rolls move the cloth forwardly, against the retardation force of the tension bars, and provide an impulse tension which peaks very rapidly. With bird's-eye diaper cloth weighing 7.9 ounces per square yard, and whose yarn count is 54 x 43 warp and filling yarns per inch, we found, upon proper correlation of the adjustable tension bars 46, 47, 49 and 50 with the energization of the brake 40, that the tension induced by the dynamic friction of the tension bars reached an average maximum value of approximately 33.8 pounds per 27 inches width during the "travel portion" of the cycle. When the advance of the cloth web was arrested, the tension had decayed to an average minimum value of approximately 11.25 pounds per 27 inches width. This minimum tension was the cloth tension at which the next successive application of drafting force produced a peak in tension corresponding to that of the first application of tension. At the same time, the 11.25 pounds minimum tension represented the tension exerted on the cloth by the static friction of the tension bars to achieve in the cloth, together with the holding force of the electric brake, a condition of momentary equilibrium for the short interval (i.e. the "dwell period") when the cloth

was at rest. Such minimum tension therefore, maintained the stretch of the cloth to an extent at least equal to, and probably greater than, any residual strain in the cloth.

FIG. 31 illustrates the cloth tension curve for the specific bird's-eye cloth referred to above. The breaking strength of this cloth per 27 inches width was found to be 1045 pounds. As shown by the curve, the maximum tension of 33.8 pounds induced in the cloth during the "travel portion" of the cycle is reached practically instantaneously upon the application of the drafting force and then, during the remainder of the "travel portion," decays to the minimum tension of 11.25 pounds to which the fabric is subjected practically throughout the entire "dwell portion" of the cycle.

It will be appreciated that as a result of adjusting cloth tension, there may occur a demand for more or less cloth from the supply roll and the depth of the loop L will vary. Suitable adjustment of the cloth loop is made automatically by the photoelectric cells, and may be supplemented by hand adjustment of the machine operation, if necessary or desired.

It should be understood that the foregoing disclosure of tension control is not limited to the tension bars noted, but that other methods for controlling retardation may be used, including electrical and hydraulic means.

Resin Supply and Application Apparatus

Referring next to the step of resin application, indicated diagrammatically in FIG. 1 as station D, we provide a suitable resin supply apparatus (not shown) supported by the machine frame. We also provide a resin heating and impregnating mechanism which receives resin from the supply apparatus and which is mounted on the machine frame as hereinafter described.

We have found that successful high-speed resin hemming requires a carefully metered amount of resin to be applied to the cloth and the resin must be forced uniformly into the cloth and its yarn with relatively great pressure. These objectives are realized by a novel spider applicator assembly which comprises, essentially, a rotating bar frame supported in a carriage adjustable on the machine sides 4 and 6. The carriage is formed with the sides 64 and 66 through which is located a shaft 67, as shown in FIGS. 7 and 10. At the opposite ends of shaft 67 are gears 68 and 70 meshing with respective racks 68' and 70' on the frame sides 4 and 6. By adjusting the gears on the racks with a hand crank, the carriage may be set in a position suitable for dealing with any desired length of cloth to be cut from the web W.

Between the carriage sides 64 and 66 is mounted a spider shaft 69 supporting spider bars 69a, 69b, 69c, 69d, 69e and 69f, as shown in FIG. 13. The shaft 69 has one end extending outwardly from the machine side to support in fixed relation thereon a Geneva wheel 71 which is adapted to be indexed by a Geneva driver 71' on a driver shaft 72 (FIG. 10). The shaft 72 is supported between the carriage sides 64 and 66 and carries a worm wheel 73 which meshes with a worm 74 (FIG. 7). The worm 74 is fixed to a sprocket 75 driven by a chain 76 from shaft 18. Worm 74 provides a means of obtaining synchronization between the main machine shaft 18 and Geneva driver shaft 72, irrespective of the longitudinal position of carriage sides 64 and 66 in the machine.

Cloth W is advanced from the tension bars through a spring loaded cloth guide 79 and along a horizontal path immediately above the spider bars (FIGS. 7, 13).

Anchored between the sides 64 and 66 is a transverse bar 81 (FIG. 12). Secured to this transverse bar 81 is a doctor blade support 82 carrying a primary doctor blade 82' (FIG. 13). This doctor blade may be adjusted by screws 83, 83' (FIG. 12) with respect to the arc of travel of the spider bars to provide larger or smaller amounts of resin being retained by the bars after having passed through a resin container 84 in which a body of resin 85, preferably in liquid or viscous form, is received (FIG. 75

13). In addition to the primary doctor blade 82', there is also provided a secondary doctor blade support 86 carrying a secondary doctor blade 86. The doctor blade 86 may be adjusted by screws 87, 87' (FIG. 12), and wipes 5 a spider bar which previously had been wiped by the doctor blade 82' (FIGS. 14-18).

A plastic or resinous adhesive of suitable formulation, as indicated above, is allowed to overflow into the container 84 from a heating reservoir 88 (FIGS. 12, 13). A 10 constant supply of resin may be pumped to the heating unit 88 from a supply apparatus (not shown) through a conduit 89.

In the reservoir 88, heating is accomplished in any suitable manner, as by controlled resistance heaters and, in 15 addition to this heating action, we also provide for heating the resin in the container 84 by means of a water bath retained in a receptacle 95 (FIG. 13). The water bath is heated by resistance heaters 96, 96' immersed in the water. In the water bath is a temperature sensing device 20 97, and in the resin container, at a point near to the spider, is a second temperature sensing device 98. These sensing devices provide for a heat control to govern resin consistency.

In accordance with the invention, the spider bars are 25 rotated and dipped into the heated body of resin, each bar picking up a small quantity of resin. As the bars are indexed around toward a cloth engaging position, they first are contacted by the primary doctor blade 82' which removes some of the resin (FIG. 14). Thereafter, the 30 second doctor blade 86 operates to attenuate the resin left on the bar so as to leave a very thin film (FIGS. 15, 17). By this double doctor means, a precise amount of resin can be applied as a film V (FIG. 18) to provide for satisfactory impregnation of a sharply defined band of resin 35 V1 (FIG. 3) without an excess amount being left on the surface of the cloth, especially along the borders of the band.

By rotating each bar against a set of two doctor blades in an arc as described, we not only can provide for a 40 careful metering of a thin film of resin, but also can provide for shaping the resin film so that it has a tapering thickness and is relatively thinner along the edges of the bar (FIGS. 17, 18). With this specific film control described, we are enabled to avoid transferring an excess 45 of resin to the cloth, which excess, if present, would result in an unsightly appearance and might cause difficulty in curing. With the resin film of a relatively crowned cross 50 sectional shape, as shown in FIG. 18, pressure of the bars operates to force the relatively larger quantity of resin at the center of the bar into the cloth with slight amounts being squeezed out towards opposite edges of the bar, thereby effecting a distribution of resin into the cloth in the form of a band of uniform thickness and having sharply defined border characteristics.

55 This novel resin film control of the invention is devised for use with relatively large pressures, and as one suitable means of exerting pressure against the cloth, while contacted by the resin impregnating bar at an opposite side, we provide a top backing bar 99 which is adapted to be pressed down against the cloth by air cylinders 100, 100' (FIGS. 11, 16). These air cylinders are actuated 60 in timed relation to each revolution of the main drive shaft 18 of the machine by suitable electrical controls.

The combined action of the indexing spider applicator 65 and the top backing bar 99 operates to exert pressure of a magnitude which is capable of squeezing substantially all of the film of resin on a spider bar into the cloth. With the pressure and film control noted, resin is forced all the way through the cloth to provide a thorough impregnation.

70 With this resin applicator apparatus, we may also provide a cloth elevating device consisting of a transverse bar 101 vertically movable by actuating links 102, 102' (FIG. 13) to automatically lift the cloth slightly when the machine ceases operation. This automatic lifting is

11

accomplished by an air cylinder solenoid 193, and insures that the cloth is maintained clear of accidental contact with the resin on the spider bar.

Of course, the resin need not be in either liquid or viscous form, but may be in the form of a paste, powder or even a tape, with application to the web W by suitable means appropriate to the nature of the resin.

Resin Curing Apparatus

After a band of resin V1 is impregnated in the manner described above, the cloth advances into register with the dielectric curing station E of FIGURE 1. The dielectric heating unit is shown in detail in FIGS. 19-25 and also appears in FIGS. 5, 8-10. Certain highly desirable advantages of speed and quality of curing are realized with dielectric curing. However, the apparatus introduces problems which require precise control of the cloth travel and of register of each resin band, as hereinafter described.

An important and essential part of this resin curing apparatus are especially designed electrodes for use in carrying out a dielectric curing operation with respect to a narrow band of resin impregnated in cloth. It is pointed out that the configuration of a band of resin V1 necessarily requires an elongated electrode structure which can be brought into close proximity to the band, on the opposite surfaces of the web of cloth. Of course, the electrodes must be held away from the cloth while the wet resin band is moving into register with its curing position. The resin and the cloth in which it is impregnated thus constitute a fixed dielectric body to be energized. Therefore, the curing effect must be completed all along a narrow electric field inside of which the resin band must be located, and the cure must be performed in a very short time interval on the order of a fraction of a second, depending on the speed of processing desired. These are rigorous requirements for dielectric heating and we have found they can only be satisfied by a relatively high power input according to the formula

$$W = E^2 2\pi F_C (\text{P.F.})$$

where

W=watts of power

E=voltage

F=frequency in cycles per second

c=capacitance of the load in Farads

P.F.=effective power factor of load.

In order to meet the conditions present in a band of impregnated resin in cloth with a formula such as that noted above, one becomes limited to varying the voltage and/or frequency in order to increase power input to a satisfactory point. In the method of the invention it has been found desirable, in order to provide sufficient power for curing resin in the short time interval noted, and with a minimum of voltage breakdown, to utilize rather high frequencies of the order of 80 megacycles per second, depending upon the loss factor of the resin employed. Furthermore, the resin-cloth combination in the required configuration presents a very low electrical loss factor and to make certain that the efficiency is kept up, the energizing circuits are required to be constructed in a manner such that losses are at a minimum.

With these important points in mind, we have devised a heating apparatus which includes a special electrode configuration for accomplishing the desired objectives. A part of the dielectric apparatus is contained in a housing denoted by the arrow Z, and is mounted at the top side of the machine frame, as illustrated in FIGS. 5, 9, 10 and 19. Suitable electrical components for producing the high frequency power are maintained within the enclosure body Z. The electrodes through which the electrical energy is transmitted to the resin are supported below the electrical components at positions just above and just beneath the plane of travel of the web of cloth W passing through the machine.

12

Attention is directed to FIGS. 19 to 25 inclusive, where-
in the novel electrodes of the invention are disclosed. In
these figures numerals 104, 104' denote one set of comple-
mental electrode components and numerals 105, 105'
denote a second set of supplemental electrode compo-
nents. As will be observed from an inspection of FIGS.
20 and 23, these electrode components consist of elon-
gated bodies of semi-elliptical cross section. These elon-
gated bodies preferably are composed of aluminum and
the lower components 104', 105' are capable of vertical
reciprocating movement. The upper components 104,
105 are spaced just slightly above the plane of travel of
the web to be clear of contact with the cloth when in
motion. Because of the high frequencies which are re-
quired in dealing with the resin band curing problem, the
electrodes must be carefully formed to avoid arcing.
The elliptical cross sectional shape of the electrodes are
designed to avoid corners at which arcing may take
place. In addition, the ends of the electrode components
are recessed in the manner illustrated in FIGS. 19-21,
and in the recessed ends of the lower components are
retaining clip elements which, in the case of electrode
component 105', are designated 105a. Each clip 105a is
secured by a screw 105b and is reversely bent so that it
may snap into engagement with the supplemental recess
in the electrode component 105. Similarly, the electrode
components 104, 104' are recessed and clipped. This
recessed and interlocking arrangement of the electrodes is
important in preventing undesirable arcing.

30 The dielectric carriage Z consists of carriage sides 106, 106' joined together by fixed aluminum channels 107, 107' (FIGS. 19, 22, 23, 25). Through the carriage sides 106, 106' is located a shaft 108 at opposite sides of which are gears 109, 109' meshing with respective racks 68', 70' 35 of the frame sides 4 and 6. By adjusting the gears on the racks, we may set the dielectric carriage in coordination with the setting of the resin application carriage for any given length of diaper or other cut textile article to obtain proper registration of the band of adhesive.

40   Mounted between the carriage sides 106, 106' is a pivotable shaft 110 to which is keyed an arm 111 (FIG. 25) the outer end of which is pivotally connected to the plunger of an air cylinder 112. The air cylinder is mounted on the frame 105' as shown in FIG. 19, and is operated in timed relation with the main machine shaft 13. Air cylinder 112 pivots shaft 110, causing arms 111 and 113 to impart action to links 114, 114', thereby lifting vertically movable channels 115, 115' along guide posts 116, 116' (FIGS. 19, 22, 25) until the electrode components 104' and 105' engage the cloth against components 104, 105 and form complete electrodes, as shown in FIG. 24.

In accordance with the preferred embodiment of the invention, the cloth web is advanced intermittently to the curing station so that the successive resin bands are stopped intermediate of, and in slightly spaced relationship to, each of the two sets of electrode components. As the cloth comes to rest in a condition of momentary equilibrium, the electrode components are closed and energized and provide lines of high potential so that curing, as illustrated diagrammatically in FIG. 24, may take place in an extremely short time interval without objectionable conditions developing. We have found that with such an electrode arrangement as has been disclosed, we are able to 60 cure a resin band in approximately six-tenths of a second. This time interval is so short that substantially no deleterious effects are caused in either the resin or the cloth. The electric field indicated diagrammatically in FIG. 24 65 is of a relatively narrow span, i.e. approximately three-quarters of an inch, and the band V1 must be in substantially equally spaced relation to each of the inner surfaces 104a and 105a of the electrodes, which means regulation 70 within one-eighth of an inch at all times. If this band V1 overruns or falls short, faulty curing occurs, and the resin 75 remains tacky and offsets on to the drafting rolls and inter-

rupts operation. The method of tension control described earlier ensures proper registration of the resin band between the electrodes.

We have discovered that, as a result of forcing a heated resin into the cloth fibers under pressure, and then within an interval of a fraction of a second subjecting the resin and cloth to very high frequency dielectric heat, a surprising and novel consequence occurs. As the dielectric heat strikes through the resin band, there may be observed a volatilization phenomenon. A volatile component, apparently consisting of moisture in the cloth and, possibly, some small part of resin plasticizer, is instantaneously volatilized by the intense dielectric heat and forces its way out through the resin, and the resin band V1 takes on an appearance closely simulating the weave pattern of the cloth.

An exceedingly important improvement in the dielectric heating equipment, which makes possible this rapid curing, is the combination of the particular electrode configuration with the means for tuning these electrodes to the work load in the dielectric body of resin and cloth. It will be appreciated that in an elongated electrode there are strong tendencies for voltage differences to occur along the electrode which will, of course, result in non-uniform heating in adjacent cloth areas where resin is to be cured. This problem is rendered more difficult by reason of the fact that each of the electrodes must be divided into two components, one of which will lie above the cloth and the other of which must lie below the cloth and be movable into contact with the upper component. These components must each be at the same potential in order that they may be resonant with the generator since, without resonance, there will be inadequate power transmission.

It is pointed out that the specific electrode construction and connecting coil means shown in the drawings meets these requirements of providing proper resonance for maintaining voltages substantially uniform all along the electrode lengths. Thus, to ensure substantially uniform voltages being maintained, we find that we may provide a plurality of tuning coils such as coils X1, X2 and X3, as noted in FIG. 19. Tuning coil X3 is also shown in FIG. 23. By choosing a plurality of coils as X1, X2 and X3 and spacing these coils approximately as indicated in FIG. 19, we find a uniform voltage may be obtained when these coils are connected across the electrode components 104, 105 as shown in FIG. 23. Similarly, we provide tuning coils X4, X5 and X6 which are connected across the electrode components 104, 105.

In this coil arrangement it is pointed out that the three coils X1, X2 and X3 function as tuning coils for tuning the electrodes to a desired frequency. Coils X4 and X6 also act as tuning coils, while coil X5 functions both as a tuning coil and a coupling coil. The combined effect of all of these coils is to provide a substantially uniform voltage condition all along each one of the four electrode components.

To further make certain that the components of each pair of electrodes will be at the same electrical potential after the lower components have been retracted and then returned to cloth engaging position, we have devised the special interlocking recessed clip means indicated in FIGS. 20 and 21. This is illustrated by clip 105a which functions to provide an electrical connection between the electrode components 105, 105', and is effective in helping to prevent variations in potential between the ends of those members.

Cloth Metering and Cutting Mechanism

The band of resin impregnated into the cloth leaves the curing station in a condition which is substantially free from tackiness and passes into contact with the metering rolls M and M1 without resin adhering to the surfaces of the rolls. Rolls M, M1 as earlier described are moved through a predetermined arc of rotation to provide for intermittent travel of a desired length or segment of

75

cloth, and these rolls produce the cloth drafting forces intermittently by the crank and gear mechanism earlier described.

If desired, we may provide for sources of heat being located in some convenient location adjacent to the rolls by means of which heat may be radiated, or reflected, against the surfaces of the rolls M and M1. Also, we may provide for heating the guide rolls M2 and M3 below roll M, shown in FIGS. 1 and 26. Suitable heating means for rolls M, M1, M2 and M3 are indicated in FIG. 1 by numerals 117, 117', 117". Heating element 117 also appears in FIGS. 5 and 8 at the right hand sides thereof. We have found that heating the rolls in the manner described operates to exercise a desirable secondary processing effect in which the resin band in the cloth, although set to a point where it is no longer tacky, nevertheless, undergoes further curing or setting and a calendering action. An important characteristic of a resin or plastic hem which has received this calendering heat is that the cloth fibers which are cut at the cutting station G are found to have substantially increased resistance to fraying and raveling when subjected to repeated laundering operations or other use conditions.

From the rolls M2 and M3 the cured resin band passes to cutting shears at a cutting station G. Here a cutting mechanism of conventional form, such as an Alfa shear mechanism 124, is mounted in frame extensions 36 and 37 (FIGS. 8-10). This Alfa shear is actuated by a conventional linkage 125 driven by a cam follower 126 and cam 127 on shaft 18 (FIG. 26) to cut the cured band V1 centrally of its width. Rolls M2, M3, 128 and 128' apply sufficient tension to the web W to maintain the uniform state of cloth elongation previously achieved, thereby ensuring registration of the resin bands at the cutting station. With respect to rolls 128, 128', this is accomplished as follows: Rolls 128, 128' are spaced close to rolls M2, M3 and shear 124 (FIGS. 10, 26, 27). Thus, immediately after the web W is severed medially of the resin band V1, the cut end of the advancing web is seized by the rolls 128, 128' to subject the portion of web W below rolls M2, M3 to tension to ensure that a uniform state of cloth elongation exists before the next resin band is advanced for registration at the cutting station. Preferably, the surface speeds of rolls 128, 128' should exceed slightly the surface speeds of rolls M2 and M3 for this purpose. From the cutting station G the cut diaper passes to the discharge rolls 128, 128' and thence to conveyor K.

Automatic Cycling Mechanism

The various functions performed by the preferred mechanisms described above occur in a definite timed relationship to one another and the sequence and duration of the several different functions for one typical operating cycle are indicated diagrammatically in FIG. 30. As noted therein, the cloth feeds during the period in which the main machine drive is rotating through an arc of 180°. The electric brake starts to operate just before the cloth comes to rest.

In the second half of the main drive shaft rotation, and with the cloth at rest and stretched and held in a condition of momentary equilibrium, the brake is holding for most of this dwell: the Geneva is off; and both the resin applicator and the electrodes close and then open. High frequency heat is applied just after the electrodes are closed.

Automatic cycling of certain functions illustrated by the diagram of FIG. 30 may be accomplished by means of a special limit switch arrangement supported at one side of the machine (FIG. 6). A cam plate 152 is mounted on the end of the main machine shaft 18 for rotation therewith. Secured to the side of the machine is a small supporting bracket 153 consisting of an A frame at the apex of which is mounted a stationary shaft 154 (FIG. 6). On this shaft are supported arms

155a, 155b, 155c, 155d, as shown in FIG. 9, holding limit switches 151, 156b, 156c, 156d. These limit switches are actuated at timed intervals by small nodes located on different radii on the face of the cam plate 152.

A separate cam control is provided for the electric brake mechanism, and this cam control is shown in detail in FIGS. 27-29. A cam 157 energizes limit switch 158 and operates to close a circuit through the electric brake 40. The limit switch is suitably supported on posts 158a and is adjustable with respect to the axis of the cam 157 so as to come into contact with a variable dwell 157a. With this arrangement, as the operating cycle speed is varied, the microswitch 158 is moved across the face of the cam 157 thereby increasing the lead time for energizing the electric brake.

It will be understood that we may practice the method of the invention with woven, unwoven, knitted or any other fiber and yarn assemblages of textiles fabricated from any desired class of fibers. We may also practice the dielectric heating step of the invention without cutting all or even any of the resin bands which are applied to the web.

Although we have employed the term "resin" frequently, we do not intend to limit the invention to an impregnating material which is necessarily a resin, nor necessarily a liquid. We may use as a bonding impregnant other adhesives or other types of plastic binders—either wet or dry—which can be combined along a narrow width or section of the web to anchor fibers so that they may be cut and separated to form suitable artificial selvages.

We may still further desire to apply the method and apparatus of the invention, in any one of its various forms, to produce a variety of cut pieces, such as curtains, towels, tablecloths, bed linen, flags and the like, in keeping with the scope of the invention, as defined by the appended claims.

We claim:

1. In a method of hemming in which narrow bands of an adhesive material are impregnated at spaced intervals transversely of a web of fabric by advancing the fabric web to successive adhesive application and curing stations, the step of stretching the fabric web while it is advancing to, through and from said stations an amount at least as great as any residual strain in the fabric, whereby the bands in the web of fabric are advanced at a uniform rate for registration at the curing station regardless of any variations in the stretch characteristics of the fabric.

2. The method of claim 1 further including the step of curing the adhesive bands by subjecting them to an external source of heat for a period of time less than one second at the curing station.

3. In a method of hemming in which narrow bands of an adhesive material are impregnated at spaced intervals transversely of a web of fabric by advancing the fabric web, under the influence of a drafting force, to successive adhesive application and curing stations, the step of subjecting the web while it is advancing to, through and from said stations to retardation means in opposition to the drafting force to stretch the fabric an amount at least equal to any residual strain in the fabric, whereby the bands in the web of fabric are advanced to a uniform rate relative to the application and curing stations regardless of any variations in the stretch characteristics of the fabric.

4. In a method of hemming in which narrow bands of an adhesive material are applied under pressure at spaced intervals transversely of a web of fabric and the bands are advanced successively, under the influence of a drafting force, to heat setting and fabric cutting stations, the steps which comprise

(1) engaging the fabric while it is advancing to, through and from said stations against friction surfaces to tension the fabric to impose thereon a uni-

5

form state of stretch which is at least equal to any residual strain therein and

(2) regulating the tension imposed by the friction surfaces in accordance with variation in the residual strains of the fabric to maintain the fabric in such uniform state of stretch, whereby each band advances at a constant rate for successive registration at the curing and cutting stations.

5. The method of claim 4 wherein the step of engaging the fabric against the friction surfaces includes advancing the fabric along a sinuous path, and wherein the step of regulating the tension imposed by the friction surfaces consists in varying the curvature of said sinuous path to change the area and intensity of engagement of the fabric with the friction surfaces.

6. In a method of hemming in which narrow bands of an adhesive material are applied under pressure at spaced intervals transversely of a web of fabric by intermittently advancing the fabric web along a path of travel past adhesive application and curing stations, the steps which include

(1) subjecting the web as it advances to retardation means to stretch the web of fabric during its advancement to, through and from said stations an amount at least equal to any residual strain in the fabric,
25 (2) applying bands of adhesive to the fabric web,
(3) periodically stopping the advance of the web to register an adhesive band at the curing station and
(4) exerting a holding force on an advanced portion of the stationary web while releasably engaging a rearward portion of the web by the said retardation means to hold the intervening portion of the stretched web under tension to achieve a condition of momentary equilibrium.

7. In a method of hemming in which narrow bands of an adhesive material are applied under pressure at spaced intervals transversely of a web of fabric by intermittently advancing the fabric web to adhesive application and curing stations, the steps which include

(1) applying bands of adhesive to the web of fabric,
(2) periodically stopping the advance of the web to register an adhesive band at the curing station,
(3) exerting a holding force on an advanced portion of the stationary fabric web while releasably engaging a rearward portion of the web by friction surfaces to hold the intervening portion of the fabric under tension to achieve a condition of momentary equilibrium to maintain registration of the adhesive band at the curing station while the web is at rest, and
(4) regulating the extent of engagement of the fabric with the friction surfaces in accordance with variations in the residual strains of the fabric to maintain the fabric in a uniform state of stretch which is at least equal to any residual strain therein whereby dimensional change in the fabric while at rest is substantially avoided.

8. The method of claim 7 further including the step of subjecting the registered adhesive band to an external source of heat for a period of time less than one second to cure the adhesive while the web is at rest.

9. In a method of hemming in which a web of fabric characterized by residual strains is furnished from a supply, and in which narrow bands of an adhesive material are impregnated at spaced intervals transversely of the web by intermittently advancing contiguous segments of the fabric web along a path of travel through successive adhesive application and curing stations, the steps which include

(1) subjecting the web as it advances to retardation means to stretch the fabric while it is advancing to, through and from said stations an amount at least equal to any residual strain in the fabric,
75 (2) applying bands of adhesive to the fabric web,

75

(3) periodically stopping the advance of the web to register an adhesive band at the curing station and
 (4) exerting a holding force on an advanced portion of the web while releasably engaging a rearward portion of the web by the said retardation means to maintain the intervening portion of the stationary web in a stretched condition at least equal to the maximum residual strain in the fabric.

10. In a cloth hemming machine having mechanism for engaging a web of cloth and forming therefrom cut lengths of the cloth with plastic hems, the method of:

- (1) advancing the web to, through and from successive plastic application and plastic curing stations under a tension sufficient to stretch the cloth an amount at least equal to any residual strain therein. 15
- (2) applying at the plastic application station narrow bands of a plastic material transversely of the web at spaced intervals thereof,
- (3) subjecting the plastic bands at the curing station to an external source of heat for a period of time less than one second to cure the plastic, 20
- (4) advancing the plastic bands to a cloth cutting station while maintaining the web under a tension

sufficient to stretch the cloth an amount at least equal to any residual strain therein and

(5) then severing the web while so tensioned medially of the plastic bands to form the cut fabric lengths.

11. The invention of claim 10 further including the step of regulating the tension on the cloth in accordance with variations in the residual strains thereof to maintain the stretch of the cloth at least equal to any residual strains therein.
